UNITED STATES PATENT OFFICE.

GILBERT P. RITTER, OF CHICAGO, ILLINOIS.

DRAFT-GEAR FOR RAILWAY-CARS.

No. 839,203.

Specification of Letters Patent.

Patented Dec. 25, 1906.

Application filed October 11, 1902. Serial No. 126,921.

To all whom it may concern:

Be it known that I, GILBERT P. RITTER, a citizen of the United States, residing at Chicago, in the county of Cook, State of Illinois, have invented certain new and useful Improvements in Draft-Gear for Railway-Cars; and I hereby declare the following to be a full, clear, and exact description of the same, reference being had to the accompanying drawings, in which—

Figure 1 is a horizontal central section of a draft-gear embodying my invention, the cheek-plates which form the housing guides and stops being in elevation. Fig. 2 is a vertical central section of the same. Figs. 3 and 4 are horizontal central sections similar to Fig. 1, showing the position of the operative parts in draft and buffing, respectively. Fig. 5 is a detached perspective view of one of the members of the friction-follower; and Fig. 6 is a modified form of my improved draft-rigging, showing the use of a pair of the friction-followers.

Like symbols refer to like parts wherever they occur.

My invention relates to that class of draft-gear for railway-cars in which the normal ultimate capacity of the spring resistance is increased by a frictional resistance, which also decreases the violence of the reaction of the spring when the load thereon is released, and these results I accomplish in such manner that the device is rendered light, compact, and of few parts, easily assembled and readily repaired.

To this end the main feature of my invention embraces the combination, in a draft-gear, of a spring, a follower comprised of friction elements having friction-faces and contacting inclined faces, the parts being immovably seated one on another, and a friction element or elements which coact with the first-named friction elements and are movable with relation thereto.

There are other (minor) features of invention, all as will hereinafter more fully appear, and be particularly pointed out in the claims.

I will now proceed to describe my invention more fully, so that others skilled in the art to which it appertains may apply the same.

In the drawings, A is a draw-bar or coupler-shank having secured thereto, by the rivets or bolts 1^a 1^a and filling-pieces 1^b 1^b, the yoke B.

C is a casing or housing, preferably rectan-

gular in cross-section, in the present instance shown as open at the end nearest the coupler A; but the same may be open at both ends, if desired, a follower being substituted to perform the function of the rear end 1^c thereof. The forward portion of the casing C is enclosed on all sides, while the rear portion is or may be composed merely of the walls 2^c, thus lightening the housing. 65

The interior of one end of the housing C, and either integral therewith or detachable, if desired, is provided with friction faces or elements 3^c, disposed parallel to the line of motion of the coupler, while the exterior of 70 said housing is provided with one or more longitudinal ribs 4^c 4^c and 5^c 5^c, (see dotted lines,) which travel in grooves g in the cheeks or guides G, and the ribs 4^c 4^c also serve, by abutting against either the one or 75 the other set of stops 1^g 1^g and 2^g 2^g of the cheek-plates G, to limit the longitudinal movement of the casing or housing C.

D and E are substantially similar friction elements, together forming a spring abutment and friction-follower, shown as cored for sake of lightness, the former bearing upon the spring and the latter upon the coupler when the device is in its normal position. (See Fig. 1.) Each of the friction elements 80 D and E has a friction-face parallel to its line of motion and may be also provided with an extension d and e, respectively, in the same plane therewith and extending inwardly beyond the end of the spring F when it is desired to increase the frictional area, and the 85 said friction-face and extension contact a corresponding friction-face 3^c on the interior of the housing C; but the extensions d and e may be omitted, if desired, and the members 90 D and E made counterparts. 2^d and 2^e are correspondingly-inclined faces of the friction blocks or elements D and E, respectively, which by contacting each other cause an outward thrust or pressure transverse to the 95 line of motion of said blocks D and E in a plane perpendicular to the friction-faces of the casing C when the spring F is compressed, while at the same time being seated at rest upon each other. 100

F is a spring or resilient medium, one end of which is seated upon the friction element D and the other end of which bears upon the end 1^c of the casing C or its equivalent. 105

G G are cheek-plates provided with guide-ways g (see Fig. 2) and the stops 1^g 1^g and 2^g 2^g, the latter preferably detachable, which 110

serve to limit the travel of the casing or housing C, and the said cheek-plates G are also the means of attaching the device to the car-framing by bolts or otherwise.

5 In the modification shown in Fig. 6 of the drawings a set of the elements D and E are employed at each end of the casing, which is stationary and the ends of which, $g' g'$ and $g^2 g^2$, serve as stops to limit the movement of the respective sets of elements D and E.

The several parts of the device may be assembled by first inserting the spring F in the casing C, next inserting the friction elements D and E, after which the yoke B is passed around the casing C and riveted or bolted to the coupler-shank A, which bears against the end of the friction element E. The cheek-plates G G, with stops $1^e 1^e$ removed, having been secured to the car-framing, the casing C, containing the operative parts of the mechanism, is then inserted in the guideways $g g$, after which the stops $1^e 1^e$ are secured in place, thus completing the device.

The construction being substantially such as herein pointed out, the operation of the device will be as follows: The device being in its normal or unstrained position, as shown in Fig. 1, a buffing movement of the coupler (see Fig. 4) will cause the rear end of the coupler-shank to force the friction elements E and D rearwardly, the casing C being held against retreat by the stops $2^e 2^e$ of the cheek-plates G G, thus compressing the spring F, and since the friction elements D and E are incapable of motion transverse to their line of travel on account of their contact with the walls of the casing or housing C a frictional resistance is developed between the walls of said casing and the elements D and E as the said parts move or travel relatively to each other, and by reason of the inclined contacting faces of the friction elements D and E the frictional resistance is proportional to the compression of the spring F. Upon cessation of the buffing strain the operative parts return to their normal positions in the same manner as they were displaced. The device having returned to its normal position, a pulling movement of the coupler (see Fig. 3) causes the yoke B to advance the casing C, (to the right, Fig. 1,) while the friction elements D and E are prevented from retreat by the stops $1^e 1^e$, which bear upon the friction element E, the spring F being compressed and friction created between the friction elements E and D and the coacting friction element or casing C, as before explained for the buffing operation.

It may be observed that since the compression of the spring is induced by the force applied to the draw-bar acting through the wedges D and E and since one wedge can transmit pressure to the other only in a direction which makes the angle of friction with the normal drawn to their contacting faces,

it is obvious that each wedge, although restrained from lateral movement, induces pressure upon the casing, for the reason that the line of direction of the force between the wedges, already alluded to, is at an angle to the friction-faces of the casing C. As, therefore, the force transmitted from one wedge to the other increases the pressure between the wedges and casing proportionately increases and the frictional resistance to the movement of the draw-bar is thereby correspondingly increased.

The principle of operation of the modification shown in Fig. 6 is similar to that of the construction shown in the principal figures of the drawings. The casing is stationary, and a second set of friction elements D and E is substituted to perform the follower function of the end 1^e of the casing C, one set of elements D and E operating in draft and the other in buffing, their travel being limited by the stops $g' g'$ and $g^2 g^2$, which in this construction may form part of the casing.

Having thus described my invention, what I claim, and desire to secure by Letters Patent, is—

1. In a friction draft-gear, the combination with a coacting friction element, of a plurality of friction elements relatively movable with respect thereto and having friction-faces parallel to the friction-faces of the coacting friction element and contacting inclined faces immovably seated one on another, and means for inducing relative movement and pressure between the relatively movable friction elements, substantially as and for the purposes specified.

2. In a friction draft-gear, the combination with a relatively movable coacting friction element, of a plurality of coacting friction elements having inclined contacting faces immovably seated one on another, and means for inducing relative movement and pressure between the relatively movable friction elements, substantially as and for the purpose specified.

3. In a friction draft-gear, the combination with a relatively movable coacting friction element, of a plurality of coacting friction elements having inclined contacting faces immovably seated one on another, a spring, and means for compressing said spring, substantially as and for the purposes specified.

4. In a friction draft-gear, the combination with suitable cheek-plates having stops or abutments, of a casing closed at one end and having its interior walls parallel, said casing movable between the abutments of the cheek-plates, a spring within the casing, and a follower comprised of friction elements having correspondingly-inclined contacting faces and friction-faces in contact with the interior wall of the casing, substantially as and for the purposes specified.

5. In a friction draft-gear, the combination

with a movable casing having friction-faces on its interior, of a plurality of coacting friction-elements having inclined contacting faces immovably seated one on another, a 5 spring, and means for compressing said spring, substantially as and for the purposes specified.

6. In a friction draft-gear, the combination with a spring, of a casing provided with plane friction-faces disposed parallel to the line of motion of the coupler, a spring-seat having a friction-face engaging the casing, and a follower 10 having a friction-face engaging the casing, said spring-seat and follower each having contacting faces inclined with respect to the friction-faces of the casing to cause their resilient thrusts upon said casing to lie in a plane normal to the friction-faces of the latter when the mechanism is subjected to 15 strain substantially as and for the purposes specified.

7. In a friction draft-gear, the combination

with a spring, of a casing provided with plane friction-faces disposed parallel to the line of motion of the coupler, a spring-seat having a 25 friction-face engaging the casing, a follower immovably seated upon the said spring-seat at all times during the operation of the mechanism and having a friction-face engaging the casing, the contacting faces of said spring-seat and follower being inclined with respect to the friction-faces of the casing to cause their resultant thrusts upon said casing to lie in a plane normal to the friction-faces of the latter when the mechanism is subjected 30 to strain, substantially as and for the purposes specified.

In testimony whereof I affix my signature, in presence of two witnesses, this 11th day of October, 1902.

GILBERT P. RITTER.
